STONE MOUNTING FOR BRACELETS
OR OTHER ARTICLESFrederick W. Engel, Jamaica, N. Y., assignor to
Engel Brothers, New York, N. Y., a partnership

Application July 21, 1949, Serial No. 105,987

2 Claims. (Cl. 63—26)

1

This invention relates generally to bracelets and more particularly to means for mounting and retaining stones in the individual linked members of a bracelet.

The main object of the invention is the provision of novel, simple and practical means for mounting and securing a stone in each of the linked members of a bracelet, in such manner that the stone will be securely held in its setting and kept clean in that dirt is excluded from the undersides of the stone. In ordinary mountings of the class referred to, the stone is held only by the opposed side walls of the link housing so that it is not only subject to longitudinal movement along the housing but also to soiling of the undersides of the stone or scratching thereof. Since such stones are usually provided with foil on their undersides in order to maintain their sparkling effect, any injury to the foil reduces or destroys the sparkle of the stone.

The above broad as well as additional and more specific objects will be clarified in the following description, wherein characters of reference refer to like-numbered parts in the accompanying drawing. It is to be noted that the drawing is intended solely for the purpose of illustration, and that it is therefore neither desired nor intended to limit the invention to any or all of the exact details of construction shown except insofar as they may be deemed essential to the invention.

Referring briefly to the drawing, Fig. 1 is a perspective view of the instant bracelet worn on the wrist.

Fig. 2 is a perspective view of one of the link housings in which the stones are mounted, prior to linking the housings together.

Fig. 3 is a perspective view of one of the arcuate eyelets used in linking successive housings together.

Fig. 4 is a perspective view showing the housing of Fig. 2 provided at each end with an eyelet such as shown in Fig. 3 and end ears of the housing turned down against the eyelets.

Fig. 5 is a sectional view taken on the line 5—5 of Fig. 4, but shows a plurality of housings linked together instead of only the one housing shown in Fig. 4.

Fig. 6 is a perspective view of the auxiliary insert which, in combination with the linked housings above mentioned, constitutes the essence of the instant invention.

Fig. 7 is a perspective view of a pair of adjacent linked housings, showing one of the housings with the said insert mounted therein.

2

Fig. 8 is a sectional view taken on the line 8—8 of Fig. 7.

Fig. 9 is a perspective view of one of the stones which are mounted in the said linked housings.

Fig. 10 is a sectional view taken on the line 10—10 of Fig. 9, showing the foil covering the undersides of the stone.

Fig. 11 is a perspective view of a pair of adjacent linked housings with the stones mounted therein.

Fig. 12 is a sectional view taken on the line 12—12 of Fig. 11.

Fig. 13 is a sectional view taken on the line 13—13 of Fig. 12.

15 Referring in detail to the drawing, the numeral 15 indicates a bracelet of the type referred to, composed of a plurality of linked housings 16 each having a stone 17 mounted therein, each stone having a coating of foil 18 on its 20 undersurfaces, as shown in Fig. 10.

Each housing 16 is stamped out of a sheet metal blank into the form shown in Fig. 2, and includes the bottom wall 19, the opposed side walls 20, and the opposed end ears or tabs 21, 25 the side walls having co-planar ridges 22 formed on their inner sides near the top thereof.

Each housing 16 is linked to its adjacent housing by means of an arched sheet metal eyelet 23 which includes the frame 24 and the opening or 30 window 25 therethrough. As shown in Figs. 4 and 5, each tab 21 of each housing 16 is passed through the opening 25 of an eyelet 23, and the tabs are then doubled back against the floor 19, and the tab 21 on one end of the next adjacent 35 housing 16 is then also inserted through the opening 25 and doubled back. In this manner, the successive housings 16 are linked together and are pivotal through an arch with respect to each other.

40 Ordinarily the stones 17 are mounted in the housings 16 and supported merely between the ridges 22 of the walls 20, as shown in Fig. 13, the upper edges of the walls 20 being turned in to retain the stone. It is apparent that in this 45 common form of mounting, the stone is subject to movement longitudinally of the housing 16, and the bottom surfaces of the stone are exposed to dirt and subject to becoming scratched or worn.

50 This invention proposes the use of the insert shown in Fig. 6, this insert comprising a sheet or strip of any suitable material, such as metal, deformed into a pair of adjacent portions or planes 27 at an angle to each other; as illustrated, 55 this angle is obtuse, but it may of course be acute

or even a right angle. Each plane 27 has an opening 28 therethrough, and the extremities on end edges 29 of the insert are turned in toward each other at such an angle that the edges 29 lie in mutually parallel planes.

An insert 26 is inserted into each housing 16 in the manner illustrated in Figs. 7, 8 and 12, with the peak 30 of the angular insert being positioned substantially midway of the length of the housing 16 and transverse with respect thereto and in contact with or positioned slightly above the floor 19. In thus positioning the insert, the rounded doubled back tabs register in the openings 28 of the insert 26 and thus serve to maintain the insert in the position just described. The edge extremities 29 thus also provide end walls for the mounting, and upon insertion of the stone 17 as shown in Fig. 12, and turning in the edges of the side walls 20 above the ridges 22, the stone is held not only by these side walls but also by the end walls 29 provided by the insert 26 as well as having the undersides of the stone supported and protected by the planes 27. Thus the stone is locked in the housing 16 on all four sides and is prevented from any movement, either longitudinal or transverse, with respect to the housing. It is to be noted that in referring to the portions 21 of the insert 26 as "planes" it is not intended to limit these portions to absolutely flat members, as they may be curved or arched and yet function equally well.

Obviously, modifications in form or structure may be made without departing from the spirit or scope of the invention.

I claim:

1. A mounting for a stone, comprising a housing having a bottom wall, opposed side walls extending upward from said bottom wall, opposed end tabs extending upward from the end edges of said bottom wall, said tabs being doubled back substantially against said bottom wall thereby providing transverse bulges adjacent said end edges of the bottom wall, and an insert, said insert comprising a strip bent at an angle less than a straight angle intermediate its length thereby providing a transverse peak thereon, the portions of said strip on the sides of said peak having openings therethrough, the extreme edge

of each of said portions of said strip being bent at an angle to said portion, said last-named angle having a degree such that said extreme edges of said portions lie in substantially parallel planes, said insert being positioned in said housing with said peak at right angles to said side walls and said bulges registering in said insert openings and thereby positioning said insert with said extremes edges thereof forming end walls for said housing positioned at right angles to said side walls of the housing, the cup-like recess formed by said insert and said side walls being receptive of a stone having a bottom contour substantially similar to said recess.

2. A mounting for a stone, comprising a housing having a bottom wall, opposed side walls extending upward from said bottom wall, transverse bulges adjacent the end edges of the bottom wall, and an insert, said insert comprising a strip bent at an angle less than a straight angle intermediate its length thereby providing a transverse peak thereon, the portions of said strip on the sides of said peak having openings therethrough, the extreme edge of each of said portions of said strip being bent at an angle to the said portion, said last-named angle having a degree such that said extreme edges of said portions lie in substantially parallel planes, said insert being positioned in said housing with said peak at right angles to said side walls and said bulges registering in said insert openings and thereby positioning said insert with said extremes edges thereof forming end walls for said housing positioned at right angles to said side walls of the housing, the cup-like recess formed by said insert and said side walls being receptive of a stone having a bottom contour substantially similar to said recess.

FREDERICK W. ENGEL.
